[57] **CLAIM**

The ornamental design for a shoe midsole, as shown and described.

DESCRIPTION

FIG. 1 is a left side elevational view of a shoe midsole showing my new design therefor;
FIG. 2 is a right side elevational view thereof;
FIG. 3 is a front elevational view thereof; and,
FIG. 4 is a rear elevational view thereof.
The portions of the midsole top which are not shown form no part of the claimed design.
